UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

CAR-UNDERFRAME.

1,244,769.

Specification of Letters Patent. Patented Oct. 30, 1917.

Application filed November 21, 1916. Serial No. 132,588.

To all whom it may concern:

Be it known that I, ALLEN E. OSTRANDER, residing at Ridgewood, county of Bergen, State of New Jersey, and being a citizen of the United States, have invented certain new and useful Improvements in Car-Underframes, of which the following is a full, clear, and exact description, such as will enable others skilled in the art to which it applies to make and use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

The object of the invention is to produce a railway car underframe and superstructure in which is utilized railway rails of the conventional type, wherever such rails are adapted to be placed.

Another object is to combine with such railway rails a bolster center filler casting comprising two parts separable vertically and adapted to clamp between its parts the end portions of the webs of such rails, and also to provide convenient means for attaching the inner ends of draft sills, which are preferably of Z-shape in cross section.

Another object is to utilize the bolster center filler casting as an anchor for the ends of truss rods disposed below the center sill formation, which comprises a plurality of such railway rails with their heads in juxtaposition and the normal bottom or base flanges vertically disposed and nearer the sides of the car.

Other objects and advantages will be hereinafter more specifically pointed out.

The car underframe is illustrated in the accompanying drawings in which:

Figures 1 and 1^a represent a plan view of a little more than one-half of the underframe of the car, the flooring and other parts of the car being omitted for the sake of clearness;

Fig. 2 is a composite transverse sectional view showing on the left a transverse section taken on the broken line 2—2 of Fig. 3^a and on the right illustrating a half-section at the bolster which section is taken on the line 2^a—2^a of Fig. 3;

Figs. 3, 3^a and 3^b constitute the equivalent of a single longitudinal view of the car, the portion in Fig. 3 representing a section on the line 3—3 of Fig. 1, that portion included in Fig. 3^a being another section taken on the line 3^a—3^a of Fig. 1^a and toward the extreme right of the figure illustrating the car structure in side elevation, and Fig. 3^b being a continuation of that side elevation to and slightly beyond the bolster at the opposite end of the car;

Fig. 4 is a composite view illustrating on the left a transverse half-section at the cross bearer, being taken on the line 4—4 of Fig. 3^a, while on the right another transverse half-section is shown adjacent the central and outer struts, this section being taken on line 4^a—4^a of Fig. 3;

Fig. 5 is a fragmentary transverse section through the center sill of the car looking toward the rear side of the bolster as indicated by the section line 5—5 of Fig. 3;

Fig. 6 is an inverted plan view of the upper casting of the bolster center filler; and

Fig. 7 is a plan view of the lower casting or said bolster center filler.

Referring to the parts, 1 indicates parallel rails which extend from within the zone of one bolster 2 at one end of the car to within the zone at the opposite end of the car, it being understood that, while the drawings represent but half of a car underframe, it is duplicated at the opposite end, in the usual manner. As indicated in the sectional view, Fig. 4, the heads 3 of the rails 1 are spaced a slight distance apart and the base flanges 4 are connected by rivets extending therethrough to the inner hopper sheet 5 through which said rivets 6 in the drawings, likewise extend, and connecting the webs of the rails 1, struts 7 coöperate with filler pressings or castings 8, between which members, 7 and 8, though these members are not in vertical alinement, the rails pass.

The end portions of the rails 1 are cut away along the oblique lines 10, as best shown in Fig. 1, to provide a space 11 for the insertion of the king pin through the opening 12 in the bolster, usually provided therefor, while the flanges of said rails extend preferably through the bolster from rear to front, that is, from the middle of the car toward the end sills.

As will be noted in Figs. 1 and 2, the draft

sills 13 are of Z-shape in cross section. They extend beyond the end sills 14, which are preferably of built-up plate-girder formation through and beyond the bolsters 2, 5 where they lap the end portions of said rails 1.

The draft sills are provided with vertical webs 15, bottom flanges 16 and top flanges 17, the top flange and the web being of approximately the same length, but the bottom flange 16 is cut away at 18 to facilitate the connection of the truss rods, hereinafter referred to, with the bolster center filler casting.

15 This bolster center filler casting is of peculiar formation and comprises a lower member 20 and an upper member 21, between which are clamped the end portions of the rails 1, which form the center sills of the car intermediate the bolsters.

To facilitate assembly, this bolster center filler casting is split horizontally, as shown in Fig. 3, and in its lower portion the usual king pin socket 12 is provided, in addition 25 to which integral brackets 22 are cast upon said lower portion 20 and said brackets 22 serve as anchors for the ends of truss rods 23 which are held by bolts 24 in said brackets.

30 The upper member 21 of the bolster center filler casting extends rearwardly, as shown in Figs. 1 and 3, and laps said rails 1 and, as shown in said figures, vertical rivets extend through the horizontal webs 25 and 26 35 of the bolster center filler casting parts to connect the end portions of the rails 1 thereto.

Likewise, the vertical webs 15 of the draft sills are secured by direct rivet connection 40 with the flanges 4 of said sills, said rivets being indicated at 29 in Fig. 1, and to reinforce the draft and center sill connection, a top cover plate 30 is provided which extends at least from the end sill 14 through 45 the bolster, and for some little distance therebeyond, toward the middle of the car, as shown in plan view of Fig. 1. This top cover plate 30 is secured by direct rivet connection with the upper flanges 17 of the 50 Z-shaped draft sills. Coöperating with the center sill construction, thus far described, are the truss rods 23 which are anchored at their ends in the brackets 22 and support intermediate their ends the struts 7, which 55 struts in turn bear against the lower faces of the center sill rolled sections 1.

The cross bearer, a plurality of which may be employed when desirable, is formed of either pressed or cast diaphragms 35 60 which, with the fillers 36 and 8 and top and bottom cover plates 39 and 40 complete said cross bearer. The cross bearer extends transversely of the car a sufficient distance to underlie the side sills 41, as shown in 65 Figs. 2 and 4, and connected with the outer

end portions of the cross bearer are filler castings 42, which underlie said side sills 41. The diaphragms 35, as may be noted in Fig. 1^a, are arranged in pairs on each side of the center sill rails 1, being spaced 70 and placed back to back. Each casting 42 has a portion or flange between the spaced webs of the diaphragms with which it is associated, which flange is riveted to and connects both of said spaced diaphragm 75 webs. Castings 42, one at each end of the cross bearer, also make connection between said cross bearer and the side sills 41, side stakes in the form of railway rails being attached in their lower portions to the normal bottom flanges of the rail side sills and to the flanges of the castings 42. Coöperating struts 43 and truss rods 44 serve to support the said sills 41 intermediate the bolsters, to which latter member the ends 80 of the truss rods 44 are connected by pins 45 which extend through eyes or openings in the ends of said truss rods and through brackets 46 at the end portions of said bolsters, which are shown as being integral 85 parts of the bolster diaphragms 48, but which, obviously, may be separate members secured to said bolsters.

The bolsters are of the built-up type comprising diaphragms 48 which are preferably 90 of cast metal, though they may be pressed, of top and bottom cover plates 49 and 50, respectively, which extend for a sufficient distance along the lengths of said diaphragms 48 across the bolster, and the middle portion of the bolster comprising 100 the bolster-center-filler-casting including the members 20 and 21, hereinafter referred to.

As before described, the bolster serves as an anchor for the end portions of the truss 105 rods 44.

The webs of the rails 1 are connected intermediate the bolsters by the horizontal plate or baselike portions 61 of the struts 7, through which horizontal portions extend 110 rivets 62, which also pass through the horizontal webs of said rails 1, thereby tying these rails together and intermediate these horizontal baselike portions 61 and the bolsters, the rails are also tied together by 115 plates 64, which form loops for the rails and also serve as supports for supporting chocks 65 which rest under the inclined floor 66 of a hopper car body. The loops or plates 64 are connected by rivets 67 with the bottom 120 flanges of the rails, thereby firmly anchoring 125 said loops in position.

Instead of spacing the heads 3 of the rail portions of the center sills as shown to provide the conventional spacing for draft sills, 125 said heads may be brought into contact throughout their entire length, thus bringing nearer together the inner hopper sheets 5 and increasing the capacity of the car, in which event fillers would be required be- 130

tween the vertical webs 15 of the draft sills and the bottom flanges 4 of said rails to provide the $12\frac{1}{8}$ inch spacing of draft sills called for by M. C. B. requirements.

5. What I claim is:

1. In combination in a railway car under-frame, center sills comprising a plurality of railway rails with their heads in juxtaposition and their base flanges spaced farther apart, draft sills secured to the outer sides of said rails and a bolster within which extend the center sills and draft sills.

10. In combination in a railway car under-frame, center sills comprising a plurality of railway rails with their heads in juxtaposition and their base flanges spaced farther apart, shaped draft sills having vertical webs directly connected with said rails, and a bolster within the zone of which lap the 20 rails and said draft sills.

15. In combination in a railway car under-frame, center sills comprising a plurality of railway rails with their heads in juxtaposition and their base flanges spaced farther apart, draft sills having vertical web portions and reinforcing flanges lapping said rails and secured directly thereto.

20. In combination in a railway car underframe, center sills comprising a plurality of railway rails with their heads in juxtaposition and their base flanges spaced farther apart, draft sills lapping and being secured directly to flanges of said rails, and a bolster comprising a center-filler-casting 35 extending above and below said rails.

25. In combination in a railway car underframe, center sills comprising a plurality of railway rails with their heads in juxtaposition and their base flanges spaced farther apart, draft sills secured directly to said rails and a bolster center-filler-casting having a part extending below said rails and being directly connected thereto.

30. In combination in a railway car under-frame, center sills comprising a plurality of railway rails with their heads in juxtaposition and their base flanges spaced farther apart, draft sills secured to and forming longitudinal extensions of said center sills, 45 a two-part bolster-center-filler-casting connected respectively with said center sills and draft sills and truss rods connected to said filler-casting.

35. In combination in a railway car under-frame, center sills comprising a plurality of railway rails with their heads in juxtaposition and their base flanges spaced farther apart, and a combined truss-rod, anchor and bolster-center-filler-casting extending over 40 and under said rails.

45. In combination in a railway car under-frame, center sills comprising a plurality of railway rails with their heads in juxtaposition and their base flanges spaced farther apart, flanged draft sills, a two-part bol-

ster - center - filler - casting overlapping said rails, and a truss rod connected with said casting and assisting in the support of said rails.

5. In combination in a railway car under-frame, center sills comprising a plurality of railway rails with their heads in juxtaposition and their base flanges spaced farther apart, draft sills connected directly to said base flanges, a bolster and a bolster-center-filler-casting connected directly to said draft sills and overlapping said rails.

10. In combination in a railway car under-frame, center sills comprising a plurality of railway rails, draft sills secured directly to said rails, a bolster within which extend the center sills and draft sills, truss rods connected to the bolster below said rails and struts between said truss rods and rails.

15. In combination in a railway car under-frame, center sills comprising a plurality of railway rails with their base flanges vertically disposed, Z-shaped draft sills having vertical webs directly connected with said base flanges, and a bolster within the zone of which the rails extend.

20. In combination in a railway car underframe, center sills comprising a plurality of closely juxtaposed railway rails, draft sills having vertical web portions and reinforcing flanges lapping said rails and being secured directly thereto and a two-part bolster - center - filler - casting inclosing end portions of the rails.

25. In combination in a railway car under-frame, center sills comprising a plurality of railway rails with their heads in juxtaposition and their base flanges spaced farther apart, draft sills lapping and being secured directly to flanges of said rails, a bolster comprising a center-filler-casting extending above and below said rails and truss rods anchored in said center filler casting and supporting the middle portion of said rails.

30. In combination in a railway car under-frame, center sills comprising a plurality of railway rails having oppositely beveled end portions, draft sills secured directly to said rails, a bolster-center-filler-casting having a part extending below said rails and being directly connected thereto and a king-pin socket in said center-filler casting intermediate end portions of the rails.

35. In combination in a railway car under-frame, center sills comprising a plurality of railway rails with their heads in juxtaposition and their base flanges spaced farther apart, Z-shaped draft sills secured to and forming longitudinal extensions of said center sills, a two-part bolster-center-filler-casting connected respectively with said center sills and draft sills, truss rods connected to said filler-casting and extend-

ing from bolster to bolster only, and means connecting the truss rods to the lower portion of said center-filler-casting.

16. In combination in a railway car underframe, center sills comprising a plurality of railway rails with their heads in juxtaposition and their base flanges spaced farther apart, a combined truss rod, anchor and bolster-center-filler-casting extending over and under said rails, side sills formed of railway rails and truss rods anchored in bolsters at each end and supporting the middle portions of all of said rails.

17. In combination in a railway car underframe, center sills and side sills comprising a plurality of railway rails, a bolster, flanged draft sills and a two-part bolster-center-filler-casting overlapping some of said rails, a truss rod connected with said casting and other truss rods connected di-

rectly to the end portions of said bolster and assisting in the support of said rails.

18. In combination in a railway car underframe, center sills and side sills comprising a plurality of railway rails with horizontal webs and having their base flanges vertically disposed, draft sills connected directly to the base flanges of the center sills, a bolster and a bolster-center-filler-casting connected directly to said draft sills and overlapping said rails, truss rods and struts interposed between the truss rods and the webs of said rails.

In witness whereof I have hereunto set my hand in the presence of two witnesses. 35

ALLEN E. OSTRANDER.
